UNITED STATES PATENT OFFICE.

EDWARD W. KEOUGH, OF MIDDLEBORO, MASSACHUSETTS.

SHUTTLE-BOX-OPERATING MECHANISM.

1,426,392.

Specification of Letters Patent. Patented Aug. 22, 1922.

Application filed April 17, 1922. Serial No. 554,260.

To all whom it may concern:

Be it known that I, EDWARD W. KEOUGH, a citizen of the United States, residing at Middleboro, in the county of Plymouth and State of Massachusetts, have invented certain new and useful Improvements in a Shuttle-Box-Operating Mechanism, of which the following is a specification.

My invention relates to an improved shuttle box operating mechanism adapted to be used in connection with the Knowles loom.

The primary object of the invention is to provide a roller motion mechanism for operating the shuttle boxes designed to replace the positive fixed motion now in use, and which is extremely efficient in operation and will eliminate the grave defects existing in the looms at the present time, which comprise picker sticks, pickers, shuttle smashes, displaced shuttles, and the like.

Another object of the invention is to provide an improved and novel means of mounting the mechanism referred to.

With these and such other objects in view, as will be apparent from the description, my invention resides in the novel construction and arrangement of parts hereinafter described and claimed and illustrated in the accompanying drawings, of which—

Figure 1 is an end elevation of one side, commonly known as left hand side of the Knowles loom, equipped with the improved roll motion mechanism;

Figure 2, a side elevation of the mechanism illustrated in Figure 1;

Figure 3, an end elevation of the right hand end of the loom, equipped with the improved roll motion mechanism; and

Figure 4, a side elevation of a mechanism illustrated in Figure 3.

The invention is shown as applied to a Knowles loom and in the drawings, the end bars of the loom are illustrated as at 20, which carry on the usual brackets 21 the bell crank levers 22 carrying the quadrant gears 23, and connected with the operating arms 24. Extending laterally of the end frames 20 are brackets 25 carrying shafts 9 on which are journaled pinions 26 for engagement with the quadrant gears. These elements described comprise the ordinary construction of the Knowles loom and form no part of the present invention.

The invention in detail comprises rollers

9, 10 and 11, mounted on the shafts supported on the brackets 25 heretofore described, and suitably connected with pinions 26 in such manner that on rotation of the rollers the corresponding pinions will be actuated to move the quadrant members 23. At each side of the loom is disposed a pair of these rollers which carry chains 26 adapted to be wound thereon and connected at one end to the rollers and at their opposite ends to the uppermost ends of bell crank levers 1, 3, 5 and 7, supported on rock shafts 27, disposed on brackets 12 and 14 extending laterally from the main frame 20. The opposite end portions of the bell crank levers 1, 3, 5 and 7, are pivotally connected to vertically operating rods 28 connected at their lower ends with levers 16 pivoted on the rock shaft 29 carried by the main frame 20 adjacent the bottom thereof, to which in turn are pivoted the levers 15 carrying at their opposite ends the operating rods 30. Rods 28 and levers 15 and 16 are part of the ordinary construction of the loom and form no part of the present invention, other than in their connection with the bell crank levers 1, 3, 5 and 7.

As a means of preventing the quadrant gears 23 from sliding out of mesh, I provide a check comprising a casting 13 fastened to the main frame of the loom on the inside of the levers, as illustrated in Figure 1. This check member is adjustable over the quadrant levers to prevent them jumping out when the vibrators comprising the ordinary construction of the loom are removed.

Rollers 9, 10 and 11 are mounted on independent shafts and work alternately so that as the levers are drawn back the chains will be wound upon the rollers at one side of the loom and unwound on the opposite side and vice versa; this operation occurring through the medium of the ordinary operating mechanism of the loom not shown actuates the shuttle boxes in the ordinary manner and provides a direct and even pull at all times on the box operating mechanism, thereby preventing any occurrence of the objectionable happenings as noted hereinbefore.

While I have illustrated and described certain details entering into the construction and operation of the invention, I desire it to be understood that I do not intend to limit myself to these, but that any

such may be used as will fall within the scope of the invention as claimed.

I claim:

1. In a loom, the combination with a vibratory gear mechanism of the loom, of shafts extending laterally therefrom, rollers secured on said shafts, chains on said rollers, a connection between said chains and the shuttle box operating mechanism of the loom, whereby on rotation of the rollers movement will be imparted to the shuttle box operating mechanism.
- 10 2. In a loom, a shuttle box operating mechanism comprising the combination

with a vibratory gear mechanism of the loom, of rollers mounted on shafts extending laterally of the loom frame, means for rotating said rollers, chains attached to said rollers and adapted to be wound and unwound thereon, rock shafts carried by the loom frame, bell crank levers disposed on said rock shafts, and connection between said bell crank levers and chains at one end of the levers and connection between the opposite end of the levers and the shuttle box operating mechanism of the loom.

In testimony whereof I affix my signature.

EDWARD W. KEOUGH.
